175,139

COSTUMER OR SIMILAR ARTICLE

R. S. Allen, Dallas, Tex.

Application January 3, 1955, Serial No. 33,799

Term of patent 14 years

(Cl. D33—8)

I claim:

The ornamental design for a costumer or similar article, substantially as shown.
